GUMMED TAPE PRINTING DEVICE

Tomun Finizie, Bridgeport, Conn., and John J. Connolly, Pelham Manor, N. Y.; said Finizie assignor to Bayus Electric, Incorporated, Bridgeport, Conn., a corporation of Connecticut

Application May 9, 1950, Serial No. 160,912

4 Claims. (Cl. 101—213)

1

This invention relates to new and useful improvements in printing devices and has particular relation to a device for repeatedly printing a message on spaced portions of tape as the tape is taken from a roll.

An object of the invention is to provide a printing device of the character indicated and which is particularly applicable to printing on gummed tape.

Another object is to provide a printing device having the characteristics stated and wherein a roll of tape to be printed upon is yieldingly held in engagement with the matrix of a printing roll.

Another object is to provide a printing device adapted for the repeated printing of the same message on spaced portions of a tape and which device includes in addition to a printing roll an inking roll together with improved means for supplying ink to the inking roll.

An additional object is to provide a printing device especially adapted for the repeated printing of the same message on spaced portions of gummed tape as the latter is taken from a roll and including means whereby a roll of gummed tape may be easily and quickly mounted in the device.

Other objects and advantages of the invention will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawings:

Fig. 1 is a view with the near side of the housing or casing of the device omitted and showing the printing mechanism and roll of tape in side elevation;

Fig. 2 is a view taken as looking from the right in Fig. 1;

Fig. 3 is a view taken as looking from the left in Fig. 1, the closure for the housing or casing being shown in section;

Fig. 4 is a sectional view taken as along the line 4—4 of Fig. 1;

Fig. 5 is a top plan view showing the mounting of the ink supply and the inking roll;

Fig. 6 is a sectional view taken as along the line 6—6 of Fig. 5; and

Fig. 7 is an elevational view taken as looking from the left in Fig. 5.

Referring in detail to the drawings, wherein

2

the invention is disclosed as applied to the printing of gummed tape, at 10 is generally indicated a portion of a casing or housing. In gummed tape dispensers, there is usually incorporated a tape feeding means and a tape moistening means and a tape cut-off means. However, as such particular means form no part of the present invention, no attempt has been made to illustrate them and they may be considered as located forwardly of that portion of the machine housing which has been illustrated.

A housing 10 is shown as including a bottom wall 11, side walls 12 and 13, and a top wall 14 in the form of a cover extending down at the rear end of the machine and hinged at 15. With this construction, it will be clear that the cover 14 may be swung to an open out-of-the-way position substantially entirely at the rear of the housing 10. However, the invention is not limited to any particular housing structure and it will be clear that the housing structure may be other than that shown.

Mounted on the bottom wall 11, toward the rear thereof, is a U-shaped bracket 16 shown as fastened in place by rivets 17 passing through its bight portion 18 and as further including spaced upstanding ears 19 and 20. A pivot pin or bar 21 passes through these ears and forms the pivot mounting for parts to be described. Mounted by the pivot 21 and having their lower ends at the outer sides of the ears 19 and 20 are a pair of bracket arms 22 and 23 between them rotatably mounting a printing roller 24 for rotation on or with an axle 25. Also mounted between the bracket arms 22 and 23 and more specifically between the upper portions thereof is an inking mechanism generally designated 26 and later to be described in detail.

A bracket structure generally designated 27 and of U-shape has its bight portion 28 also mounted for pivotal movement by the pivot pin or bar 21 and then this structure includes a pair of upwardly and forwardly inclining arms 29 and 30. Through their upper inner sides and towards their free ends these arms 29 and 30 are provided with inclined slots 31 (compare Figs. 1 and 4) receiving the axle or mounting pin 32 of a roll of gummed tape generally designated 33. With this construction it will be seen that to mount the tape, the ends of its axle 32 are aligned with the upper ends of the slots 31 and the roll dropped into place. Also, at the upper sides of the arms 29 and 30 are mounted guide rollers 34 and 35 extending at the sides of the tape roll 33 and insuring rotation of the latter in a fixed plane.

Considering the bracket 27 as one member mounting the gummed tape and the bracket arms 22 and 23 as a second member mounting the printing roller 24, means are provided for yieldingly urging one of said members about its pivot in a direction whereby to yieldingly maintain the tape roll 33 and the printing roll 24 in peripheral contact.

As herein shown, a pin 36 depending from a cross member 37 extending between and supported by the arms 29 and 30 of bracket 27 is in opposing relation to a pin 38 supported from the bottom wall 11 of the housing. A coil spring 39 surrounds these pin portions and is guided by them and being an expansion spring is constantly exerting a force to rock the bracket 27 about the pivot 21 in a counter-clockwise direction whereby to carry the roll of tape 33 against the printing roller 24.

Because of the pressure of the roll of tape 33 against the printing roller 24, there is a tendency for the bracket comprising the arms 22 and 23 to also swing in a counter-clockwise direction on the pivot pin or bar 21. Such tendency on the part of the named bracket arms is prevented by a stay or brace 40 comprising a plate-like member hinged or rotatable on or with a pin 41 supported by the bracket side arms 22 and 23 and at its free or lower end engaging a stop in the form of a lug 42 on the housing bottom wall 11.

When a roll of tape 33 is to be mounted in the present device, the cover or top wall 16 of the housing or casing 18 is swung on the hinge 15 to a wide open position. Then, by pressing downwardly on the upper portions of the bracket arms 22 and 23 or on the inking device generally designated 26, the printing roller is forced against a roll of tape and the entire assembly swings in a clockwise direction on the pivot pin 21 compressing the spring 39. This movement is of limited extent since only sufficient movement is necessary to free the lower end of the brace 40 from the stop lug 42 whereupon the brace is also swung in a clock-wise direction on the pivot 41 carrying the free end of the brace away from the stop lug 42.

Now the whole assembly will swing in a counter-clockwise direction and the bracket arms 22 and 23 and the parts carried thereby are swung in such counter-clockwise direction until the whole upper side of bracket 27 is exposed. Now the core or axle of a used roll of tape may be removed from the slots 31 and a new roll dropped into place to be supported by the arms of said bracket. Then the bracket arms 22 and 23 and the parts mounted thereby are swung in a clockwise direction until the brace 40 catches in back of the stop lug 42 when the whole device is again ready for use.

The bracket arms 22 and 23 include upper forwardly extending substantially horizontal parallel portions 43 and 44 respectively. Between such bracket arm portions 43 and 44 is mounted the inking mechanism 26 previously mentioned. Such mechanism comprises a sub-assembly including an ink tank or reservoir 45 extending between and rigid with spaced parallel ears 46 and 47 lying at the inner sides of the bracket arm portions 43 and 44, respectively, and pivoted thereto as on a bar 48. Extending forwardly from the upper wall of the ink tank 45 is a wall-like projection 49 below and at the ends of which are ears 50 supporting a pivot pin or rod 51 on which is mounted a bracket generally designated 52 and rotatably supporting an inking roller 75.

53 which may be comprised of felt or the like or of a hard core having a layer of felt or the like thereabout.

Bracket 52 includes a yoke-like portion comprising a pair of spaced arms 54 between the free end portions of which is rotatably mounted the inking roll 53 and then such bracket includes a bight portion 55 mounted on the pin 51 and a forwardly extending arm 56 located below the extension or wall portion 49 previously mentioned. A screw 57 is rigid at its lower end with the bracket arm 56 and passes through the wall-like projection 49 and on the screw above the arm is a nut 58. A coil spring 59 surrounds the screw 57 between the bracket arm 56 and the extension 49 of the reservoir and is constantly tending to rock the bracket and yoke 52 in a counter-clockwise direction. Movement of the yoke in such direction about the pin 51 is limited and, in fact, the yoke may be swung in the opposite direction and against the tendency of the spring 59 on tightening of the nut 58. As will later more fully appear, the combined bracket and yoke 52 is adjusted for the proper application of ink to the printing roller 24.

30 A felt pad has a portion 60 within the tank 45 and disposed against the bottom wall thereof and this pad, which is in the nature of a wick, has a portion 61 extending outwardly of the tank and disposed against the upper side of a rigid support or backing-up member 62 shown as comprising a piece of metal secured to the tank as by a screw or the like 63. Through the wick portion 61, at the upper side of the brace 62, are 35 a series of hairs or the like 63a. Normally, these hairs are bearing against the inking roller 53 whereby as the latter is rotated ink is applied to the roller from the hairs and the hairs themselves receive the ink from the portion 61 of the described wick and the latter carries the ink by capillary attraction from the interior of the tank 45. With this arrangement, overwetting or saturation of the roller 53 is avoided.

40 A member 64 is threaded through the top wall of tank 45 and such member includes a central portion or mid portion having a reduced diameter passage 65 therethrough and within the tank includes a portion or tube 66 and at its lower end bears against the wick portion 60. Through the inner end portion of tube 66 are relatively 45 large diameter openings 67 while through the upper portion of the member 64 are openings 68 aligned with similar openings 69 in a centrally thickened upper wall portion of the tank. It is noted that the openings 68 and 69 are 50 adjacent the upper wall of the tank and above the ink level therein.

55 The member 64 includes an upper tubular portion 70 into which is threaded the shank 71 of a needle valve 72 having a knurled head 73 for easy manipulation of this valve. A coil spring 74 bearing against the underside of the valve head 73 and a portion of member 64 prevents casual movement of the needle valve out of its adjusted position. A small opening 75 is provided 60 in the tubular portion 70. The opening 75 is to admit air which moving outwardly through the openings 68 and 69 is admitted to the interior of the tank 45 above the liquid level therein whereby to permit of an even movement of liquid from the tank and to prevent the formation of a vacuum in the latter.

65 When the needle valve is closed tightly, opening 75 is prevented from communication with the interior of the tank and liquid will not flow

5

from the tank. The needle valve is cracked slightly to admit of a slight entrance of air into the tank through opening 75 to cause the feed of ink. The rate of feed of ink will depend on the extent the needle valve is opened and this will be in accordance with atmospheric pressure of the place of use of the present device and permits of its proper use at high as well as low altitudes, etc.

In the complete machine, while the machine is in use, the inking roller 53 is against the hairs 63a thereby taking ink and such inking roller has its periphery in engagement with the periphery of the printing roller 24 whereby ink is transferred to the type or matrix on the latter for impression upon the tape. As the tape is taken from the roll 33, the latter rotates on an axis represented by the axle 32 and through its engagement with the printing roller the latter is rotated. Rotation of the printing roller causes rotation of the inking roller. As the tape is unwound and the roll of tape and the printing roller are rotated it will be understood that on each rotation of the printing roller a message will be printed on the tape. The same message will be printed on the tape on each rotation of the printing roller and the messages will be spaced along the length of the tape as the latter is taken from the roll.

The engagement of the inking roller with the hairs 63a is regulated by adjusting the nut 58 so as to control the position of the combined bracket and yoke 52. Then the pressure of the inking roller against the printing roller is controlled by adjustment of a finger piece 76 fixed to the outer end of a threaded shank or bar 77 threaded through a supporting member 78 fixed to the bracket arm portions 43 and 44.

Toward its inner end, shank 77 carries an enlargement 79 and forwardly of the latter a stud 80, such stud being aligned with a stud 81 on the rear wall of the ink tank 45. A coil spring 82 surrounds these studs and bears at its ends against the outer surface of the rear wall of the ink tank 45 and the inner surface of the enlargement 79 rigid with the shank 77. Clearly, on turning of the finger piece 76 in one direction, shank 77 is threaded through the bar 78 in a direction to compress spring 82 whereupon the spring bearing against the wall of the ink tank at a point forwardly of and above the pivot 48, there is a tendency to move the entire assembly 26 in an arcuate direction about the bar 48 as a center. Any such movement carries the inking roller 53 downwardly against the printing roller 24 and the pressure of any such engagement will depend on the extent to which the shank 77 is threaded through the bar 78.

Having thus set forth the nature of our invention, what we claim is:

1. In a printing device for repeatedly printing the same message on spaced portions of a tape as the same is taken from a roll, a first means for supporting a roll of tape for rotation about its own axis, a printing roller, a second means supporting said printing roller for rotation on an axis spaced from but parallel with the axis of a roll supported by the first mentioned means, means for inking said printing roller, pivot means mounting said first and second means for relative pivotal movement, releasable means restraining pivotal movement of said second means in one direction, and spring means constantly urging said first means in said one direction on said pivot means to maintain a roll 75 pivot means toward which said spring means

6

supported by said first means in engagement with said printing roller.

2. In a printing device for repeatedly printing the same message on spaced portions of a tape as the same is taken from a roll, a pivotally mounted first means for supporting a roll of tape for rotation about its own axis, a printing roller, a pivotally mounted second means supporting said printing roller for rotation on an axis spaced from but parallel with the axis of a roll supported by the first means, means for inking said printing roller, said first means being pivotally movable toward said second means to carry a roll supported by said first means into peripheral engagement with said printing roller, releasable means restraining movement of said second means in one direction, and spring means constantly urging said first means in said one direction to resiliently maintain a roll supported by the first means in engagement with the printing roller supported by the second means.

3. In a printing device for repeatedly printing the same message on spaced portions of a tape as the same is taken from a roll, a housing including bottom and side walls and a hinged top wall swingable to and from a position closing the upper side of said housing, means on the bottom wall of said housing and supporting a pivot bar above said wall, a first means for supporting a roll of tape for rotation about its own axis, a printing roller, a second means supporting said printing roller for rotation on an axis spaced from but parallel with the axis of a roll supported by the first means, inking mechanism supported by the second means and positioned for supplying ink to said printing roller, said first and second means mounted on said pivot bar for relative pivotal movement, spring means urging said first means about said pivot means in a direction to carry said roll against the periphery of said roller, a stop on the bottom wall of said housing, a stay on the second means and normally engaging said stop whereby said second means is held against movement to carry the printing roller from the roll and the latter is urged against the former by said spring means, said second means extending over said first means whereby when said cover is in open position said second means may be pressed against the first means and both such means moved about said pivot on compression of said spring to release said stay from said stop and then both said means may move about said pivot in the opposite direction and the second means moved from over the first means to expose the latter for the mounting of a new roll thereon.

4. In a printing device for repeatedly printing the same message on spaced portions of a tape as the same is taken from a roll, a housing including bottom and side walls and a hinged top wall swingable to and from a position closing the upper side of said housing, a first means for supporting a roll of tape for rotation about its own axis, a printing roller, a second means supporting said printing roller for rotation on an axis spaced from but parallel with the axis of a roll supported by the first means, inking mechanism positioned for supplying ink to said printing roller, pivot means mounting said first and second means for relative pivotal movement, spring means urging said first means about said pivot means in a direction to carry said roll against the periphery of said roller, a stop carried by said housing and disposed at the side of said

urges said first means, a stay pivoted on the second means and normally engaging said stop whereby said second means is held against movement to carry the printing roller from the roll and the latter is urged against the former by said spring means, said second means extending over said first means whereby when said cover is in open position said second means may be pressed against the first means and both such means moved about said pivot means on compression of said spring to release said stay from said stop and then both said means may move about said pivot means in the opposite direction and the second means moved from over the first means to expose the latter for the mounting 15 of a new roll thereon.
